1

3-THIOSTEROIDS AND METHOD OF
PREPARATION

Clarence G. Stuckwisch, Las Vegas, N. Mex., and Nathan F. Blau, Wichita, Kans., assignors to the United States of America as represented by the Secretary of the Army
No. Drawing. Filed Aug. 31, 1961, Ser. No. 143,265
(Filed under Rule 47(a) and 35 U.S.C. 116)

16 Claims. (Cl. 260—397.2)
(Granted under Title 35, U.S. Code (1952), sec. 266)

The invention described herein may be manufactured and used by or for the Government for governmental purposes without the payment of any royalty thereon.

The present invention relates to the preparation of sulphur-containing derivatives of cholesterol and the resulting products as new compositions of matter having Formulas I and II below:

5

10

2

wherein R is alkyl or aryl, R' is hydrogen, alkyl or aryl, 15 X⁻ is arylsulphonate, X⁻ and S⁺ indicating the ionic nature or saltlike nature of the compound, in which X⁻ is the anion and S⁺ means a positive charge-bearing ion or cation.

In accordance with the instant invention, there has 20 been made the important discovery that derivatives of Type I above can be prepared directly and in good yields by reaction of a sulphhydryl compound, RSH, wherein R is alkyl or aryl, and a cholesteryl arylsulphonate. Also, there has been made in accordance with the instant invention, 25 the discovery that compounds of Type II above can be prepared by the reaction of a sulphide, RSR, wherein R is alkyl, with a cholesteryl arylsulphonate in a polar solvent such as nitromethane or acetonitrile.

It is thought that the mechanism leading to the production 30 of the cholesterol derivatives of the present invention is represented by the following reactions using cholesteryl p-toluenesulphonate as an example:

In the above reactions, R is either alkyl or aryl. TsO is the universally accepted abbreviated formula for p-toluene-sulphonic acid radical and is known also as the tosyl radical. The plus sign at the bottom of ring B or at carbon six indicates a positive charge or diminished electron density on that carbon. The symbol S⁺ indicates, as has been noted previously, a positive charge-bearing ion or cation.

On this basis, the general reactions for the syntheses of the present invention may be expressed as follows:

In the above reaction, the arrows in the group

indicate coordinate covalent bonds contrasting with simple covalent bonds. These signs are significant with respect to the electronic constitution of the atoms and thus as regards the stability of the radical as a whole. The same explanation for the plus sign associated with sulphur in the first product of the above-indicated general

reaction is the same as has been indicated above, that is, it indicates a positive charge-bearing ion or cation, whereas the minus sign attached to the last product of the above-indicated general reaction again indicates a negative charge-bearing ion, or an anion.

In the instant disclosure and claims, by the terms "alkyl" and "aryl" are meant, respectively, so-called "lower alkyls" as represented by, but not necessarily limited to, methyl, ethyl, propyl, isopropyl, and by the aryl radicals are meant groups represented by, but not limited necessarily to, phenyl, p-tolyl, furyl, phenyl, and the like.

The sulphonium arylsulphonates of the present invention can be converted to sulphonium halides by means of ion-exchange. The derivatives of the instant invention are anti-metabolites for cholesterol in physiological processes.

It appears that the reactions involved in the present invention take place in two steps. The first step is the dissociation of cholesteryl p-toluenesulphonate into the p-toluenesulphonate ion and a resonating carbonium ion, as indicated by the "double-headed" arrow in the above-indicated reactions representing the conversion of cholesteryl p-toluenesulphonate into the cholesterol derivatives. The resonating carbonium ion then reacts with a mercaptan to yield the 3-alkylthio-5-cholestene or with a dialkyl sulphide to yield a 3-dialkylsulphonio-5-cholestene p-toluenesulphonate. Such a mechanism is significant in that it allows the reaction to proceed with retention of configuration at carbon atom No. 3 in the steroid molecule.

The process of the present invention may be illustrated by the following illustrative, although not necessarily limiting, specific examples:

35

EXAMPLE A

Five parts of cholesteryl p-toluenesulphonate, 10 parts of methyl mercaptan, and 25 parts of glacial acetic acid (all parts by weight) were placed in a pressure bottle at 30° C. for 24 hours. The crystals which separated were collected on a filter and crystallized from acetone. The thioether thus obtained was four parts by weight and melted at 126° C. This product was identified as 3β-methylthio-5-cholestene.

Analysis.—Calculated for C₂₈H₄₆S: C, 80.71; H, 11.6. Found: C, 80.44; H, 11.48.

EXAMPLE B

Five parts of cholesteryl p-toluenesulphonate, 10 parts of dimethyl sulphide, and 75 parts of nitromethane were placed in a pressure bottle and heated to 70° C. for 24 hours, or at 30° for 20 days. On cooling, crystals separated. These were collected on a filter and crystallized from methanol-ether. The recovered sulphonium compound weighted 4.5 parts by weight and melted at 195-200° C. This product was identified as 3β-dimethylsulphonio-5-cholestene p-toluenesulphonate.

Analysis.—Calculated for C₃₀H₆₀O₃₅: C, 71.5; H, 9.9. Found: C, 71.34; H, 9.6.

When an alcoholic solution of the product of Example B was passed over the chloride form of "Amberlite IRA-410" (Rohm and Haas Co.), the chloride salt of the sulphonium derivative of the steroid was obtained, M.P. 182-183° C.

65

EXAMPLE C

In Vitro Test for the Inhibition of the Biosynthesis of Cholesterol

Flasks containing rat liver homogenates in a buffered solution, with sodium acetate and 3β-dimethylsulphonio-cholestene chloride (1 mg. per flask) added, was shaken at 37° C. for approximately five hours. Control mixtures were similarly compounded, except for the omission of the steroid under examination, and treated as indicated above.

75

At the end of the incubation period the cholesterol formed in the two sets of flasks was isolated as the digitonide and determined quantitatively by the usual colorimetric method. As compared with the control tests the liver preparations to which 3β -dimethylsulfonylo-5-cholestene chloride has been added showed 77% less new cholesterol formed in the reaction mixture.

EXAMPLE D

In Vivo Test for the Inhibition of the Biosynthesis of Cholesterol

A number of rats, divided into experimental and control groups, were fed a standard diet and observed as to food consumption and gain of weight. One of the groups had the test compound (0.05%) by weight of diet added to the diet. After the two weeks on this regimen the animals were exsanguinated and the serum, liver, and adrenals were analyzed for cholesterol.

It was found that, as compared to the control groups, 3β -dimethylsulfonylo-5-cholestene chloride lowered the cholesterol concentration in the adrenal glands by 32%, while a lowering of 49% of cholesterol was observed in the adrenal glands of another group of animals that was fed 3β -methylthio-5-cholestene. Other examples of 3-thiosteroids which can be prepared by the process of this invention and which are useful as anti-metabolites for cholesterol are:

- 3β - dimethylsulfonylo - 6β - methyl - 5 - cholestene p-toluenesulphonate
- 3β - dimethylsulfonylo - 6β - phenyl - 5 - cholestene p-toluenesulphonate
- 3β - methylthio - 6β - methyl - 5 - cholestene p - toluenesulphonate
- 3β - dibutylsulfonylo - 6β - methyl - 5 - cholestene p - toluenesulphonate
- 3β - butylthio - 6β - methyl - 5 - cholestene p - toluenesulphonate
- 3β - methylthio - 6β - methyl - 5 - cholestene

The foregoing description discloses the preferred compositions of the newly discovered compounds of the present invention and the preferred procedures for their preparation; however, it will be understood that compositional and procedural details may be varied by one skilled in the art without departing from the actual invention hereby presented. Accordingly, it will be understood that it is intended and desired to embody within the scope of this invention such modifications and changes as may be necessary or desirable to adapt the invention to varying conditions and uses as defined by the appended claims.

We claim:

1. A process for preparing 3-thio derivatives of cholesterol having the formula

wherein R is a radical selected from the group consisting of a lower alkyl and aryl, and R¹ is a radical selected from the group consisting of hydrogen, lower alkyl and aryl which comprises directly reacting a mercaptan selected from the group consisting of a lower alkyl mercaptan and an aryl mercaptan with a cholesteryl arylsulphonate.

2. A process as claimed in claim 1, wherein the chole-

teryl arylsulphonate is cholesteryl p-toluenesulphonate, and the mercaptan is methyl mercaptan.

3. A process for preparing a 3-thiosteroid having the formula

wherein R is a radical selected from the group consisting of a lower alkyl and aryl, and R¹ is a radical selected from the group consisting of hydrogen, lower alkyl and aryl which comprises introducing into a pressure bottle a reaction mixture composed of cholesteryl p-toluenesulphonate, methyl mercaptan and glacial acetic acid in substantially relative proportions in parts by weight, of the respective components of the mixture of five parts, ten parts, and 75 parts, allowing the resulting mixture to react at substantially 30° C. for approximately 24 hours, collecting the resulting crystalline reaction product on a filter, and crystallizing the reaction product from acetone.

- 30 4. A composition of matter, 3-thio derivatives of cholesterol having the formula

wherein X⁻ is an arylsulphonate, X⁻ and S⁺ indicating an ionic nature of the compound in which X⁻ is an anion and S⁺ is a positive charge-bearing ion, R is a radical selected from the group consisting of lower alkyl and aryl, and R' is a radical selected from the group consisting of hydrogen, lower alkyl, and aryl.

- 50 5. A process for preparing 3-thio derivatives of cholesterol having the formula

wherein X⁻ is an arylsulphonate, X⁻ and S⁺ indicating the ionic nature of the compound in which X⁻ is an anion and S⁺ is a positive charge-bearing ion, R is a radical selected from the group consisting of lower alkyl and aryl, and R' is a radical selected from the group consisting of hydrogen, lower alkyl and aryl which comprises directly reacting a lower alkyl sulphide with a cholesteryl arylsulphonate in a polar solvent.

6. A process as claimed in claim 5, wherein the lower alkyl sulphide is dimethyl sulphide, the cholesteryl arylsulphonate is cholesteryl p-toluenesulphonate, and the polar solvent is nitromethane.

7. The process as claimed in claim 6 wherein there is employed a reaction mixture composed of cholesteryl p-toluenesulphonate, dimethyl sulphide, and nitromethane, in ratios of substantially five parts by weight of cholesteryl p-toluenesulphonate, ten parts by weight of dimethyl sulphide, and 75 parts by weight of nitromethane.

8. The process as claimed in claim 6 wherein the reaction mixture defined by claim 8 is placed in a pressure bottle, heated to substantially 70° C. for approximately 24 hours, cooling the resulting material, collecting the resulting reaction product, and crystallizing the reaction product from methanol-ether solvent.

9. The process as claimed in claim 6 wherein the reaction mixture set forth in claim 8 is placed in a pressure bottle and maintained at a temperature of substantially 30° C. for a period of 20 days, collecting the resulting reaction product, and crystallizing the reaction product from methanol-ether solvent.

10. The process of producing 3-steroid ethers of cholesterol, which comprises dissociating cholesteryl p-toluenesulphonate into the p-toluenesulphonate ion and a resonating carbonium ion by subjecting the cholesteryl p-toluenesulphonate to heat and pressure in the presence of an alkyl sulphide until a crystalline reaction product forms, and collecting the reaction product.

11. The process of producing 3-steroid ethers of cholesterol as claimed in claim 10 wherein the dissociation is effected in the presence of a polar solvent.

5 12. The process of producing 3-steroid ethers of cholesterol as claimed in claim 10 wherein the resonating carbonium ion is reacted with an organic sulphide compound selected from the group consisting of a lower alkyl mercaptan and a dialkyl sulphide to yield a reaction product selected from the group consisting of 3-alkylthio-5-cholestene and 3-dialkylsulphonio-5-cholestene p-toluenesulphonate.

10 13. A process for preparing the compounds of claim 4, which comprises directly reacting a lower alkyl sulphide with cholesteryl p-toluenesulphonate in a polar solvent by heating together the alkyl sulphide and cholesteryl p-toluenesulphonate with the polar solvent until separation of a crystalline reaction product is effected.

15 14. A process as claimed in claim 13 wherein the polar solvent is selected from the group consisting of nitromethane and acetonitrile.

15 15. The compound 3 β -dimethylsulphonio-5-cholestene p-toluenesulphonate.

20 16. The compound 3 β -dimethylsulphonio-5-cholestene chloride.
